[57] CLAIM

The ornamental design for a toilet paper holder, as shown and described.

DESCRIPTION

FIG. 1 is a top, front, and right side perspective view of a toilet paper holder showing my new design;

FIG. 2 is a bottom, rear, and left side perspective view thereof;

FIG. 3 is a top, front, and left side perspective view of a second embodiment thereof;

FIG. 4 is a bottom, rear, and right side perspective view of the embodiment of FIG. 3;

FIG. 5 is a top, front, and left side perspective view of a third embodiment thereof; and

FIG. 6 is a bottom, rear, and right side perspective view of the embodiment of FIG. 5.

FIG. 6
